[57] CLAIM

The ornamental design for a push button control station, as shown and described.

DESCRIPTION

FIG. 1 is a front elevational view of the push button control station;

FIG. 2 is a side elevational view of the design shown in FIG. 1;

FIG. 3 is a side elevational view, similar to FIG. 2, the annular button guarding element being shown in section;

FIG. 4 is a top plan view of the structure shown in FIG. 1;

FIG. 5 is a front elevational view of yet another alternate embodiment of the design;

FIG. 6 is a side elevational view of the design shown in FIG. 5;

FIG. 7 is a side elevational view, similar to FIG. 6, the annular button guarding element being shown in section;

FIG. 8 is a top plan view of the structure shown in FIG. 5; and

FIG. 9 is a fragmentary, horizontal central sectional view of the push buttons of the disclosed design.

The dominant features of the design reside in the front configuration as best seen in FIGS. 1 and 5.
